(57) **CLAIM**

The ornamental design for a pram, as shown and described.

DESCRIPTION

FIG. 1 is a front perspective view of a pram showing my new design;

FIG. 2 is a rear perspective view of the pram of FIG. 1;
FIG. 3 is a front elevation view of the pram of FIG. 1;
FIG. 4 is a rear elevation view of the pram of FIG. 1;
FIG. 5 is a left elevation view of the pram of FIG. 1, with
the right elevation view being a mirror image of the left
elevation view;

FIG. 6 is a top plan view of the pram of FIG. 1;
FIG. 7 is a bottom plan view of the pram of FIG. 1; and,
FIG. 8 is a detailed front perspective view of the pram of
FIG. 1.

The broken lines shown in the figures represent environment
and form no part of the claimed design.

1 Claim, 8 Drawing Sheets
